CLAIM

The ornamental design for a bowl sleeve as shown and described.

DESCRIPTION

FIG. 1 is a perspective view of a bowl sleeve, showing the new design on a bowl;

FIG. 2 is a perspective view thereof, without the bowl;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken line showing of the bowl in FIG. 1 is for the purpose of illustrating environmental structure that forms no part of the claimed design. The broken lines shown in FIGS. 7 and 8 depict portions of the bowl sleeve that form no part of the claimed design.
